OPTICAL SYSTEM TO FORM HIGHLY COMPRESSED BRIGHT LINE IMAGE OF LIGHT SOURCE

Arthur J. Holman, East Orange, N. J.

Application April 2, 1932, Serial No. 602,665

12 Claims. (Cl. 88—24)

My invention relates to an optical system adapted to produce a finer and brighter light line for use in recording and duplicating photographic sound records, and in the reproduction of sound from such photographic sound records. Sound motion pictures are decidedly inferior in tone quality particularly in the reproduction of music and the female voice. Although it is possible, by careful application of laboratory methods, to record with considerable fidelity sounds having frequencies up to 10,000 cycles and even higher, there is no sound equipment available at the present time which is capable of reproducing such high frequencies, even from the original sound recordings. Moreover, sound motion pictures suffer much from the further degrading of tone quality caused by inferior duplication, on the positive prints, of the original high frequency recordings. As a consequence, the timbre and color of musical selections when rendered in sound pictures, are so obviously inferior that the great majority of musical comedy motion pictures have been financial failures. The loss of the higher overtones from the reproduced human voice removes the very characteristics by means of which we are enabled to distinguish one voice from another, so it is not surprising that, at sound motion picture exhibitions, the voices of actresses are always reproduced in too low a key and are scarcely distinguishable one from another.

The upper limit of the sound frequency range, i. e. the highest pitch note, which can be recorded in a photographic sound record is dependent chiefly on three factors, namely, the linear velocity of the film across the recording aperture, the height (measured in the direction of motion of the film) of the recording light line, and the resolving power of the photographic emulsion wherein the sound is recorded. Experience has proven that the resolving power of the photographic emulsion, i. e. the size of the silver haloid grain, is not the limiting factor in determining the maximum sound frequency which can be successfully recorded at the established film velocity of 24 frames (approximately 18 inches) per second. With film velocity standardized at 24 frames per second for standard 35 millimeter film, there remains only one means of improving the quality of commercial motion picture sound recording, namely by reduction in the effective height of the sound track recording line.

The fidelity with which sounds, particularly those of high frequency, can be reproduced from a sound record is determined first, by the height of the scanning line, and second, by the combined

characteristics of the amplifying system and the loud speakers. Electrical amplification has been steadily improved and loud speakers are available for reproducing sound frequencies far beyond the working range used commercially in sound motion pictures, so here again much improvement in sound quality can be expected from the use of a finer and intrinsically brighter scanning line. Considerable theory has been developed in connection with ideal recording and reproducing which pre-supposes a recording and scanning line of infinitesimal height, and some approximations have been made as to the rate of falling off in efficiency of reproduction, particularly of the high pitch notes, as the height of the scanning line is increased to the values which usually obtain in commercial practice. From this data it appears that a reduction of only 50% in the height of the scanning line will increase the efficiency of reproduction, by several hundred per cent, of those higher overtones the absence of which is the unmistakable characteristic of "canned music."

Present practice in constructing exciter systems calls for a mechanical slit having height to width ratio equal to the proportions of corresponding dimensions of the scanning line. This proportionality between the slit and the scanning line obtains because the scanning line, which is a reduced image of the mechanical slit, is formed on the film by a high grade well corrected microscope objective. The mechanical slit is illuminated by a coil filament incandescent lamp and usually a condenser is interposed between the filament and the slit to increase the illumination on the slit. To make the system reasonably easy to adjust and to eliminate the detrimental effect of a sagging filament, the light band formed at the slit by the condenser is many times the height of the slit itself, hence the system is exceedingly inefficient as a light transmitter. It has been found impractical to make the slit much over one half inch in width, hence, for the usual length of scanning line, the optical reduction from slit to image cannot exceed 4 or 5 to 1, so theoretically, if the scanning line is to be .001 inch in height, the height of the mechanical slit will be .004 or .005 inch. A certain amount of aberration is associated with light passing an edge regardless of the type of optical system being used, and when a narrow slit is formed between two edges the multiplied aberration resulting therefrom is very detrimental to the definition of the image projected on the sound track by the objective. While the theoretical height of the scanning line may be .001 inch, the actual

height of the slit image, including aberrations, may be appreciably greater in commercial apparatus, but it is extremely doubtful if any laboratory apparatus using a microscope objective is capable of providing a scanning line less than .002" in actual height.

Exciter optical systems employing a cylindrical element in the condenser have been suggested as a means for producing a narrower scanning line, and some work has been done in this direction. While a cylindrical condenser element may increase materially the spot efficiency at the slit, it is doubtful if the increased light can be so directed through the slit as to increase the brightness of the image formed by the microscope objective. Moreover the problem of edge aberration at the slit is not solved by the use of a cylindrical condenser element.

My invention includes the use of a spherocylindrical objective system for forming a highly compressed line image of a suitable light source. Such an objective eliminates the necessity for a mechanical slit because spherocylindrical elements are bi-focal in the sense that their refracting power is different in planes at right angles, hence the image of an incandescent lamp filament may be reduced many times more in diameter than in length. With the mechanical slit eliminated the aberration problem is much simplified. I have learned from years of experience with precision cylindrical lenses that the aberrations therein are relatively less than for spherical lenses, therefore a spherocylindrical objective system offers the further advantage over the microscope objective, of improved correction.

My improved exciter optical system may be best understood by reference to the accompanying drawings in which

Fig. 1 is a plan view showing relative positions of exciter lamp, objective, film and photo-electric cell in an arrangement wherein the light beam is redirected through an angle of 90 degrees within the objective.

Fig. 2 is an elevation of the arrangement shown in Fig. 1, showing relative position of the sound track.

Fig. 3 is a plan view showing exciter lamp, spherocylindrical condenser, objective, film and also an end view of the objective.

Fig. 4 is an elevation of the parts shown in Fig. 3, showing relative position of the sound track.

Fig. 5 is a top and end view of the spherocylindrical objective showing the cylinder achromatized.

Fig. 6 is a plan view showing relative positions of exciter lamp, objective, film and photo-electric cell, and an end view of the objective. In an arrangement wherein the axis of the light beam is not turned through an angle in the objective.

Fig. 7 is an elevation of the parts shown in Fig. 6.

Fig. 8 shows another form of the objective illustrated in Figs. 6 and 7.

Fig. 9 shows an objective having separate elements, each of which are achromatized.

Referring now more specifically to the drawings in which like reference numerals indicate like parts, 1 (Figs. 1 and 2) is the incandescent filament exciter lamp provided with the usual base 2, whereby it is suitably supported, and having a coil filament 3, the diameter of which is preferably small compared to its length. A commercial exciter lamp rated at 8.5 volts and 4 amperes, having a coil .023 inch in diameter and

approximately 1/2 inch long made of wire .006 inch in diameter, is suitable for our purpose. The objective 4, having a spherical surface 5 and a cylindrical surface 6 (Fig. 3) is suitably mounted in front of the film strip 7, with the axis of symmetry of its spherical surface parallel to frame lines on the film and in line with the mid-point of the coil filament 3, the axis of coil filament 3 being at right angles to said axis of symmetry. An optically flat surface 8, on objective 4, making an angle of 45 degrees to the axis of symmetry of the spherical surface 5, provides an internal reflecting surface which redirects light from the exciter lamp through the cylindrical surface 6, to the film 7, where a sharp image of the filament 3, is formed on the sound track 9, by the combined refracting powers of the spherical surface 5, and the cylindrical surface 6.

Wherever the sound track is transparent or translucent, under the filament image, light from the exciter lamp 1, is transmitted through the film 7 into the photo-electric cell 10, which is suitably supported behind the film in such position that the light transmitted by the film falls centrally on the semi-circular shield 11, forming the cathode of the photo-electric cell 10. The film 7, is moved at uniform velocity past the scanning line, and means must be provided for so moving the film and for accurately maintaining the distance from the objective to the film surface as the film is moved, but inasmuch as the present application deals only with the exciter optical system, the film actuating and supporting mechanism and the mechanical supports for the entire sound pick-up mechanism are omitted from the specification and drawings. The axis of filament 3 lies in the plane normal to the edge of the film strip at the sound pick-up position, hence the compressed image of the filament, formed on the film 7 over the sound track 9, will be exactly at right angles to the direction of motion of the film. Provision must be made also for adjusting the exciter lamp along the axis of the objective for the purpose of focusing.

To secure a brighter image of the filament 3, at the sound track 9, a spherocylindrical condenser 12, (Figs. 3 and 4) having a spherical surface 13, and a cylindrical surface 14, is interposed between the exciter lamp 1, and the objective 4, in close proximity to the exciter lamp. The condenser 12, is so oriented that the axis of the cylindrical surface 14, is parallel to the axis of the coil filament 3. The refracting power of the spherical surface 13, is just sufficient to bend the marginal rays from the end of the filament 3, so they will be directed into the objective 4 as shown in Fig. 3. Since the axis of the cylindrical surface 14, is parallel to the axis of the coil filament 3, it is to be observed that the cylindrical surface 14, has no refracting power in the plane shown in Fig. 3, hence the rays in this plane are unaffected by the cylindrical surface, but in the plane at right angles thereto, illustrated in Fig. 4, the refracting powers of the spherical surface 13, and the cylindrical surface 14, are cumulative, hence a greater wedge angle of light may be collected and so directed into the objective that it will add to the brilliance of the image formed on the sound track by the objective 4. The condenser 12, is placed close to the exciter lamp 1, first, to collect and parallel the greatest solid angle of light, and second, to cause a minimum magnification of the filament as viewed from the position of the objective.

The objective 4, (Fig. 3) is so designed that,

for a given distance from the spherical surface 5, to the coil filament 3, and a given spacing between the cylindrical surface 6, and the sound track 9, the refracting power of the spherical surface is such as to image sharply the ends of the coil filament in the plane of the sound track on the first surface of the film 7, and the combined refracting power of the spherical surface 5, and the cylindrical surface 6, is such as to image sharply the sides of the coil filament in the same plane. The spacing of the refracting surfaces of the objective from the internal reflecting surface is such as to provide for the collecting of a maximum amount of light from the exciter lamp filament, and the concentrating of the same into a highly compressed sharply defined line image of said filament in the plane of the sound track.

To produce a compressed line image of the exciter lamp filament entirely free from color throughout its entire length, the objective 18, (Fig. 5) is made of flint glass, and a crown glass cylindrical element 16, having a convex surface 17, is cemented to a corresponding concave cylindrical surface on the flint objective 18. The exterior cylindrical surface 18, of the crown glass element 16, is of the proper curvature to produce the desired cylindrical refracting power. The crown and flint glasses are preferably so selected for index of refraction and dispersive power, that full color correction, insofar as that is possible with two kinds of glass, is obtained from the internal crown and flint cylindrical surfaces. It is to be noted that the important factor is achromatism with respect to the edges of the line image, therefore color correction of the cylindrical element (which may be slightly over-corrected to take care of the refracting power of the flint sphere as it affects the edges of the line image) is sufficient.

For the usual sound pick-up system, wherein the optical axis is straight from the exciter lamp filament to the photo-electric cell, a spherocylindrical objective of the type shown in Figs. 6 and 7, is provided. The objective 19, (see end view) has a rectangular contour, the greater dimension being parallel to the coil filament 3. A spherical surface 20, is provided on one end of the objective and the rectangular contour is beveled off toward the other end whereon is provided a cylindrical surface 21, having its axis parallel to the long dimension of the rectangle. The rectangular contour provides an increased effective aperture in the direction of the filament axis and a sufficient effective aperture for the cylindrical refracting surface, thus greatly increasing the light collecting power of the objective over that of an objective of circular contour and, at the same time, reducing the aberrations along the edge of the image because of the reduced aperture of the cylindrical lens element. In Fig. 8, is shown an objective 22, having a spherical surface 23, and an opposite cylindrical surface 24. Objective 22 is similar to objective 19 in all respects except that it has a circular contour, and, although it is somewhat cheaper to make, it is not as effective as objective 19. In Fig. 9, is shown a fully corrected objective comprised of an achromatized spherical lens 25, and an achromatized cylindrical lens 26, the elements being so proportioned and spaced as to fulfill the refracting requirements as hereinabove stated.

The 90 degree internal reflecting objective is designed for use in connection with a non-intermittent projector mechanism suitable for exhibiting applicant's improved 35 millimeter sound

film strip whereon is printed standard "silent" film frames and a relatively wide sound track. The centered position of the film frames and the position of the sound track with respect to the single row of perforations is indicated in Figs. 2 and 4, and other characteristics of the improved sound film are more fully set forth in co-pending application Serial No. 415,320, filed December 19, 1929. Means for suitably supporting the individual components of the sound pick-up system in proper relation to the film strip, and mechanism whereby the image of the coil filament may be focused sharply in the plane of the sound track are the subject of an application Serial No. 758,-429 filed December 20, 1934.

The plane of an object and the plane in which its image is sharply focused by a lens, are termed conjugate planes with respect to the equivalent center of the lens. In a lens system comprised of spherical and plane refracting surfaces, there is but one equivalent center of the system. In a spherocylindrical system, there are two equivalent centers both lying on the optical axis, the one related to a plane containing the optical axis and the axis of the cylindrical element, the other related to a plane containing the optical axis and cutting the axis of the cylindrical element at right angles. Consider, for example, the objective shown in Figs. 6 and 7. In Fig. 6, the cylindrical surface 21, has no converging power in the plane of the paper, hence the equivalent center, as related to this plane, lies on the optical axis at its point of intersection with the spherical surface 20. In Fig. 7, both spherical surface 20 and cylindrical surface 21 have converging power in the plane of the paper, hence the equivalent center of the system, as related to this plane, lies somewhere on the optical axis between these two surfaces and its exact spacing from each of them is inversely proportional to the refracting power of the surfaces. Obviously a spherocylindrical objective, to be suitable for the present purpose, must be designed, and also positioned with respect to the film, so that a pair of conjugate object and image planes will be common to both equivalent centers.

The chief advantage of my improved objective resides in the fact that a spherocylindrical objective is bi-focal in two planes, the shorter focus being in the plane through the axis of the objective and perpendicular to the axis of the cylindrical surface, and the longer focus being in the plane containing the axis of the objective and the axis of the cylindrical surface. This characteristic of spherocylindrical lenses, which produces a distortion of the image, makes it possible to compress a relatively wide object into a very fine line image, thus eliminating the necessity for symmetrical proportionality between image and object. With this proportionality eliminated, there is no need for a mechanical slit, hence slit aberrations are removed as a factor heretofore responsible in large measure for poor definition in the scanning line.

An examination of Figs. 1 and 6 shows the further optical advantage possessed by my spherocylindrical objective, which relates particularly to its ability to collect light and concentrate it into a bright well-defined line image. Since there is no mechanical slit, light from all areas of the filament facing the objective, is collected by the spherical surface and concentrated uniformly, in all directions, till it reaches the cylindrical surface where it is further concentrated, in one plane, so that it comes to a sharp focus at the

film surface. The two fundamental laws of lenses, which determine the relative sizes of object and image and the relative distances thereof in terms of the focal length, are fully complied with in the objective. It is to be observed that the equivalent center of the objective for the plane illustrated in Fig. 1, is on the axis at the spherical surface. The objective is so designed that the length of the scanning line is to the length of the filament as the mean distance from the spherical surface to the image (corrected for part glass and part air path) is to the distance from the filament to the spherical surface, when the image distance and object distance are correctly adjusted for sharp focus. In the plane at right angles to the axis of the cylindrical surface, the equivalent center of the objective lies within the objective but relatively close to the cylindrical surface, and, since the ratio of filament width to scanning line height is equal to the ratio of the respective distances of object and image from this equivalent center, it is obvious that a high reduction ratio can be obtained easily without departing from the distance relations required for the reduction in image length hereinabove specified. Thus the problem resolves itself into the determination of the required relationship of the two equivalent centers, each to the other, and also to the filament and the sound track at the scanning position. Having once recognized the advantages of the spherocylindrical combination, it is an easy matter for anyone skilled in the art of lens design to lay out an objective having the required relative refracting powers in sphere and cylinder and the correct spacing to fulfill the conditions herein specified.

The use of a spherocylindrical condenser lens as shown in Figs. 3 and 4, will increase the amount of light which may be added to the scanning line, and, if the condenser lens is well made and positioned close to the exciter lamp, the definition of the image will not be impaired. Whenever a very bright line is required and extreme fineness is not desirable or advantageous, the use of a condenser is recommended, but when an extremely fine scanning line is desired it is probably advantageous to use the spherocylindrical objective without the condenser.

While I have described and illustrated various forms of my improved spherocylindrical objective, some of which are achromatized, it is to be understood that other combinations of spherical and cylindrical surfaces may be used for the purposes specified, i. e. the projection of a compressed line image of an incandescent filament, or other light source, on a photographic sound track or on a photographic emulsion for sound recording purposes. It is also to be understood that the optical axis may be redirected differently within the objective, or exterior thereto, as mechanical parts of the film feeding apparatus may require. The appended claims are intended to cover any and all combinations of spherical and cylindrical refracting surfaces whenever such combination functions as and for the purpose specified.

Although I have described my improved spherocylindrical objective as related to sound motion pictures and more particularly to a sound pick-up system for reproducing sound in connection with motion pictures, it is to be understood that my device is useful wherever a fine bright light line may be required for any purpose, hence the appended claims are to be interpreted as covering my invention in whatsoever connection it

may be used. My device may be applied to advantage in connection with the photographic recording of sound, and it should also prove useful in the duplicating of the original sound recordings on the positive prints used for projection.

It is obvious that a toric surface might be substituted for the spherical and, or for the cylindrical surface on the objective and condenser illustrated in the drawings, and an objective and condenser thus made would be quite an improvement over the microscope objective and optical system now being used for producing the scanning line. There is a decided advantage, however, in using a cylindrical element in close proximity to the film position because it offers the only means of obtaining the maximum reduction in image height. Interchangeability of toric and spherocylindrical lenses is recognized by those skilled in optics, hence it is to be understood that the appended claims are drawn broad enough to include these and any other combination of refracting surfaces capable of functioning in the manner and for the purposes specified.

Having thus fully described my invention, what I claim is

1. In a photo-electric cell exciter system, a single element bi-focal objective having a spherical refracting surface and a cylindrical refracting surface, said cylindrical surface having several times the refracting power of said spherical surface and being positioned adjacent the image plane, said refracting surfaces being spaced to provide common conjugate planes for both focal lengths of said bi-focal objective.

2. In a photo-electric cell exciter system, a single element bi-focal objective having a spherical refracting surface, a cylindrical refracting surface and a reflecting surface, said cylindrical surface having several times the refracting power of said spherical surface and being positioned adjacent the image plane, said refracting surfaces and said reflecting surface being spaced and arranged to provide common conjugate planes at right angles for both focal lengths of said bi-focal objective.

3. An achromatized bi-focal objective comprising a flint glass element having a convex spherical refracting surface and a concave cylindrical refracting surface, and a crown glass element cemented to said flint glass element, said crown glass element having two convex cylindrical refracting surfaces one of which is suitably formed to fit into the concave cylindrical surface on said flint element.

4. An achromatized bi-focal objective comprising a flint glass element having a convex spherical refracting surface, a concave cylindrical refracting surface and a flat reflecting surface opposite said refracting surfaces, the axis of the cylinder forming said concave cylindrical refracting surface being parallel to the axis of symmetry of said spherical refracting surface and forming an angle of 45 degrees with said reflecting surface, and a crown glass element cemented to said flint glass element, said crown glass element having two convex cylindrical refracting surfaces the axes of which are parallel, the refracting power of each of said cylindrical surfaces being greater in one plane than that of said spherical surface.

5. A bi-focal objective with maximum and minimum refracting power in planes at right angles, said objective having such rectangular contour as to provide approximately equal effec-

- tive apertures ("f" values) in each of said planes.
6. An achromatic bi-focal objective comprising an achromatic element having spherical refracting surfaces and an achromatic element having cylindrical refracting surfaces, said elements being curved and spaced to provide a pair of conjugate object and image planes common to both focal lengths of said bi-focal objective, substantially as and for the purpose specified.
- 10 7. In an optical system of the character specified, the combination of a single element bi-focal condenser and a single element bi-focal objective, the planes of maximum and minimum refraction of said condenser and said objective being common to both, said planes intersecting at right angles along the axis of said optical system.
- 15 8. In an optical system of the character specified, the combination of a spherocylindrical condenser and a spherocylindrical objective each comprising a single element, said condenser and said objective being positioned on a common optical axis and being so oriented that the axes of the cylinders forming the cylindrical surfaces lie 20 in a common plane.
- 25 9. In an optical system of the character specified, the combination of a light source presenting a narrow rectangular light area, a bi-focal objective having but two glass-air refracting surfaces and being positioned with its plane of greater refracting power parallel to the short sides of said rectangular light area, and a film strip carrying a photographic sound track, said film strip being adapted and arranged to cross 30 the axis of said optical system at right angles, and said rectangular light area and said sound track lying in conjugate planes common to both focal lengths of said bi-focal objective.
- 35 10. In an optical system of the character specified, the combination of a light source presenting a narrow rectangular light area, a bi-focal spherocylindrical single element objective positioned
- with its plane of greater refracting power parallel to the short sides of said rectangular light area, said bi-focal objective being arranged to turn the optical axis through an angle of 90 degrees, and a film strip carrying a photographic sound track, said film strip being adapted and arranged to cross the axis of said optical system at right angles, and said rectangular light area and said sound track lying in conjugate planes common to both focal lengths of said bi-focal objective. 10
11. In an optical system of the character specified, the combination of a light source presenting a narrow rectangular light area, a bi-focal condenser positioned close to said light source and 15 oriented so that its plane of greater refracting power is parallel to the short sides of said rectangular light area, a bi-focal objective positioned with its plane of greater refracting power coincident with said first mentioned plane, and a film 20 strip carrying a photographic sound track, the relative spacing of said parts and the refracting powers of said bi-focal objective being such that said rectangular light area and said sound track lie in conjugate planes common to both focal 25 lengths of said bi-focal objective.
12. In an optical system of the character specified, the combination of a bi-focal objective having but two glass-air refracting surfaces spaced to provide common conjugate planes for both 30 focal lengths, a narrow rectangular light source, and a film strip carrying a photographic sound record, said objective being placed with its surface of highest refracting power in close proximity to said film strip, said parts being positioned and oriented with respect to said objective to produce a highly concentrated, sharply defined, bright line image of said light source in the plane 35 of said sound track and at right angles to the edges thereof. 40

ARTHUR J. HOLMAN.
